BLAST FURNACE STOVE GAS-PORT AND BURNER NOZZLE CONNECTION

Charles E. Genovese, Chicago, Ill., assignor to United States Steel Corporation, a corporation of New Jersey

Application October 1, 1956, Serial No. 613,295

2 Claims. (Cl. 158—7)

This invention relates to blast furnace stoves and is directed to the problem of providing a gas-tight connection between the gas-port of a stove and the nozzle of a retractable gas burner for heating the stove refractory. More particularly it relates to an improved gas-port and burner nozzle connection in the form of a water-cooled gas-seal which is comprised of a pair of water-cooled annular housings respectively mounted on the burner nozzle and the gas-port. In a manner to be described, the housings are provided with cooperating parts which move into abutting engagement with each other to form the improved connection of this invention upon movement of the burner from its retracted position to an operative firing position relative to the blast stove port.

Blast furnace stoves are operated on alternate air blowing and gas heating periods respectively, for example, of two and four hour intervals. During the air blowing operation, the stove gas-port is covered by a door while air is heated by circulation over hot refractory in the stove to provide the hot air blast for a blast furnace. At the end of the air blowing operation, the door closure for the gas-port is removed and the retractable nozzle of a gas burner is moved from a retracted position to an operative firing position in which it is connected with the gas-port and delivers a burning mixture of blast furnace gas to the stove for circulation over the refractory therein. After heating of the refractory in this manner, the burner nozzle is retracted and the door closure is placed over the gas-port to thus complete a stove operating cycle. As a result of these operations, the connection between the burner nozzle and stove gas-port is subjected to temperature variations over a wide range and thermal expansion and contraction incident to such temperature changes cause warpage of a nature which interferes with obtaining an effective gas-seal about the gas-port during the firing operation. While various forms of connections which compensate for misalignment due to thermal warpage have been proposed, such proposals have not proved entirely effective and the problem of obtaining an effective gas-seal about the gas-port during a firing operation continues to be troublesome.

One of the principal objects of this invention is to provide an improved connection for joining a blast stove burner nozzle and stove gas-port in gas sealing engagement with each other and which overcomes the problems incident to thermal warpage as a result of extreme temperature changes. In accordance with the principles of this invention, the connection between the burner nozzle and gas-port is effected by a pair of water-cooled housings which are moved into abutting and gas-sealing engagement with each other upon movement of the burner nozzle from its retracted to its operative firing position. The invention also contemplates improvements according to which the water-cooled housings form an enclosed annular chamber for a sealing ring which is compressed between the housings upon movement of the nozzle to its firing position.

Further details and advantages of the invention will become apparent from the following description in connection with the accompanying drawings which illustrate a preferred embodiment of the invention. In the drawings:

5 Figure 1 is a fragmentary side elevational and vertical sectional view of a hot blast stove burner and gas-port which are provided with the improved gas-sealing connection of this invention;

10 Figure 2 is an enlarged fragmentary sectional view showing the parts of the connection in gas-sealing engagement with each upon movement of the burner nozzle to an operative firing position relative to the gas-port;

Figure 3 is an enlarged end elevational view of the water-cooled housing for the stove gas-port;

15 Figure 4 is a sectional view taken along the line IV—IV of Figure 3;

Figure 5 is an enlarged end elevational view of the water-cooled housing for the burner nozzle; and

20 Figure 6 is a sectional view taken along the line VI—VI of Figure 5.

Figure 1 shows a conventional arrangement of a retractable gas burner 1 and a gas-port 2 opening into a hot blast stove 3 for supplying a blast of hot air to a blast furnace. The gas-port 2 is defined by a collar 4 which 25 is secured to the stove shell and has an outwardly turned flange 5 about its outer edge. The burner 1 is disposed in axial alignment with the port 2 and is shown in its retracted position relative thereto. It comprises an inner conduit 6 which is supplied with air from a motor 30 driven fan 7, a concentric outer conduit 8 which is connected with a source of blast furnace waste gas, and a nozzle in the form of a sleeve 9 for connection of the burner 1 with the gas-port 2 in a manner to be described.

35 Connection of the burner 1 and the gas-port 2 is effected by movement of the sleeve 9 to the right as viewed in Figure 1 and, for this purpose, it has a bolted connection at 10 to the outer end of the conduit 8 which has a slide mounting on a support 11 for movement of the burner 1 by a fluid pressure motor 12 between the retracted 40 position shown in Figure 1 and an operative firing position relative to the port 2. In accordance with conventional practice, the burner 1 may be stationary and the sleeve 9 may have a telescopic mounting (not shown) on the outer conduit 8 for movement between retracted and firing positions. In the operative firing position of the burner 1, sealing rings 14 and 15 on the outer end of the nozzle 9 and on the gas-port flange 5 have sealing engagement with each other as shown in Figure 2.

45 The sealing rings 14 and 15 are in the form of hollow metal housings of annular shape which are water-cooled to prevent thermal warpage. As shown in Figures 3 and 4, the ring 15 is fabricated from rings which are welded together and has a flange 16 about its outer edge which is provided with openings 17 for the reception of bolts 50 55 18 (see Figure 1) for securing it to the gas-port flange 5.

Inwardly of its flange 16, the body of the ring 15 is shaped to provide an annular chamber 19 through which water is circulated by way of inlet openings 20 and outlet openings 21 which extend through the flange 16 at the lower and upper edges of the ring 15 as viewed in Figure 3. The ring 15 has a flat surface 22 inwardly of the flange 16 which is cooled by the water circulating through the chamber 19 and which faces outwardly toward the burner nozzle ring 14 for a purpose to be described. The inner edge of the surface 22 is defined by an annular projection or ring 23 which extends axially outwardly with respect to the surface 22 and provides a flat surface 24 of annular shape facing toward the nozzle ring 14 for a purpose to be described. Door mounting lugs 25 are secured to the flange 16 and project radially outwardly 60 65 70 therefrom to provide a support for securing a door clo-

sure (not shown) over the gas-port 2 when the stove is used for an air blowing operation.

The ring 14 is cast integrally with the sleeve 9 in the form of an annular housing about its outer edge which is shaped to provide an annular chamber 26 through which cooling water is circulated by way of inlet openings 27 and outlet openings 28 which are arranged as shown in Figure 5. The outer wall of the chamber 26 is shaped to provide an annular surface 29 which faces toward the gas-port ring 15 for a purpose to be described and has a pair of spaced concentric inner and outer rings 30 and 31 adjacent its radially outer edge which project axially outwardly with respect to the surface 29 for engagement with the gas-port annular surface 22 in a manner to be described. A sealing ring 32 of a compressible material, such as natural or synthetic rubber, neoprene, or other similar material, is mounted in the space between the rings 30 and 31. The ring 32 has an axial dimension such that it projects axially beyond the outer surfaces 33 of the rings 30 and 31 as best shown in Figure 6. It has a bonded connection with an annular metal mounting plate 34 which is positioned against the annular surface 35 between the rings 30 and 31. The inner ring 30 has a plurality of slots 36 in which clamps 37 are secured by bolts 38 for clamping the mounting plate 34 against movement out of the position shown in Figures 1 and 2.

Upon movement of the burner 1 from its retracted position to its operative firing position, the burner nozzle 9 is connected with the gas-port 2 by movement of the rings 14 and 15 into abutting and gas-sealing engagement with each other. The relative arrangement of the parts of the rings 14 and 15 in this operative firing position is illustrated in the fragmentary sectional view of Figure 2. As shown in Figure 2, the surfaces 33 on the rings 30 and 31 move into abutting engagement with the surface 22 on the gas-port ring 15 to form an annular chamber 41 in which the sealing ring 32 is compressed against the surface 22, the amount of compression of the ring 32 being determined by the extent to which it projects beyond the ring surfaces 33 in its uncompressed state. Radially inwardly with respect to the sealing chamber 41, the nozzle ring surface 29 has abutting engagement with the surface 24 on the gas-port ring projection 23 to provide a seal against radial leakage of the burning gases being injected by the burner 1 into the blast stove gas-port 2. Attention is particularly directed to the fact that the seal provided by engagement of the surfaces 24 and 29 is displaced in an axial direction with respect to the seal provided by engagement of the surface 33 on the inner ring 30 with the surface 22 on the gas-port ring 15. As a consequence, gas leakage into the sealing chamber 41 has its movement baffled by these two seals and thus protects the sealing ring 32 against the action of a direct radial blast of leaking gases. In addition, the gas which does escape into the chamber 41 is cooled by the surfaces of the water-cooled parts over which it travels in movement to the chamber 41. The sealing ring 32 in the chamber 41 is thus subject only a relatively light static pressure from the moving gas and is not subject to the maximum temperature of such gases. The water flowing through the chambers 19 and 26 of course is effective to maintain the temperatures of the ring parts in sealing and abutting engagement with each other at a relatively low temperature at all times and

warpage as the result of thermal contraction and expansion is thus effectively eliminated.

While one embodiment of my invention has been shown and described it will be apparent that other adaptations and modifications may be made without departing from the scope of the following claims.

I claim:

1. In a hot blast stove having a gas-port and a retractable burner nozzle movable to and from an operable firing position relative to said gas-port, the combination therewith of a sealing device comprising a pair of annular metal housings fixed respectively to the stove and nozzle, water inlet and outlet connections to both said housings for circulating cooling water therethrough, and a resilient sealing ring fixed to one of said housings and extending in an axial direction therefrom, the other of said housings having a flat annular surface aligned with said ring and adapted to be engaged thereby to prevent escape of gases between said port and nozzle, one of said housings having an annular flange located radially inwardly of said ring and a flat annular surface located radially inwardly of said flange, the other of said housings having an annular projection aligned with said second named surface for engagement therewith, said flange and said projection cooperating to provide a baffling action on escaping gases before they reach said ring.

2. In a hot blast stove having a gas-port and a retractable burner nozzle movable to and from an operable firing position relative to said gas-port, the combination therewith of a sealing device comprising a pair of annular metal housings fixed respectively to the stove and nozzle and water inlet and outlet connections to both said housings for circulating cooling water therethrough, one of said housings having a flat annular outer surface and an annular axially extending projection located radially inwardly of said surface, the other of said housings having an axially extending compressible sealing ring, axially extending flanges on opposite sides of said sealing ring, said sealing ring having an axial length such that it projects axially beyond said last-named flanges, and a flat annular surface located radially inwardly of said flanges, said ring and flanges being aligned with said first named surface for engagement therewith, said projection being aligned with said second named surface for engagement therewith, said ring being adapted to provide a substantially gas-tight seal against gases escaping between said port and nozzle, said projection and the inner one of said flanges being adapted to provide a baffling action on gases before they reach said ring.
